UNITED STATES PATENT OFFICE.

CLYDE D. LAWRENCE, OF YOUNGSTOWN, OHIO.

ELECTRIC ELEVATOR-DOOR-OPERATING DEVICE.

1,158,064.

Specification of Letters Patent.

Patented Oct. 26, 1915.

Application filed September 9, 1914. Serial No. 860,923.

To all whom it may concern:

Be it known that I, CLYDE D. LAWRENCE, a citizen of the United States, residing at Youngstown, in the county of Mahoning 5 and State of Ohio, have invented new and useful Improvements in Electric Elevator-Door-Operating Devices, of which the following is a specification.

This invention is an improved elevator 10 door operating device for automatically opening and closing an elevator door when the elevator is stopped or started from a landing, the object of the invention being to provide an improved apparatus of this 15 kind which greatly promotes safety by insuring the automatic operation of the elevator door when the elevator is started and stopped by the attendant and which moreover prevents the elevator door from being 20 opened or closed excepting when the floor of the elevator is level or practically level with one of the floors of the building in which the elevator is used.

The invention consists in the construction, combination and arrangement of devices hereinafter described and claimed.

In the accompanying drawings: Figure 1 is a vertical sectional view of an elevator provided with automatic electrically operated mechanism for actuating the elevator door, the said figure being partly diagrammatic and disclosing the electric circuit. Fig. 2 is a detail elevation of the contact box and of the cam conductor which operates the same. Fig. 3 is a detail elevation of the cam conductor at right angles to Fig. 2. Fig. 4 is a detail end elevation of the latch and its connections. Fig. 5 is a detail side elevation of the latch and a sectional view of its connections.

For the purposes of this specification an elevator car is indicated at 1 and the shaft in which the car operates is indicated at 2. The shaft is provided at each landing with 45 a sliding door 3 which is here shown as having hangers 4 at its upper side provided with rollers 5 which bear on a track rail 6. The door is provided with a pivotally mounted latch 7 which is for engaging a keeper 8 at the side of the door opening against which the door closes. A translating device 9 is employed for operating the latch and is here shown as a solenoid which is vertically arranged and the core 10 of which is connected to the latch by a rod 11, so that when

the windings of the solenoid are charged the core is drawn upwardly and the latch raised and released from the keeper 8.

The door is provided at its upper end at a point near its center with a stud 12 which 60 operates in a slot 13 in a lever bar 14 the said lever bar being pivotally connected at its upper end to the shaft as at 15, and being also provided with a slot 16. This slot is engaged by a stud 17 which projects from 65 the connected cores of the solenoids 18-19 which are horizontally arranged and secured to the shaft.

At one side of the car is a cam 20 which is vertically arranged, is substantially semi-cylindrical, and is provided on its curved cam surface with a pair of spaced conducting strips 21-22 which are preferably made of copper. The car controller lever 23 is provided with a cam 24 to operate the movable element 25 of a switch 26, said switch including an electrode 27 carried by the movable element and also including a pair of contacts 28-29 which are respectively connected to the conducting strips 21-22 of the 80 cam 20. An electric conducting cable 30 is connected to the movable element of the switch as at 31 and is also connected to the junction box 32 in the elevator well. A conductor 33 connects the contact 28 with the 85 conducting strip 21, a conductor 34 connecting the contact strip 29 with the conducting strip 22. A contact box 35 is arranged at each landing in the elevator shaft, at a suitable height according to the height of the 90 car and is provided with circuit closers 36-37. The circuit closer 36 comprises a conducting spring plate or bar 38 which is secured at one end as at 39 and provided at its free end with a contact which normally 95 is disengaged from an electrode 40 which is connected by a wire 41 to the windings of the solenoid 19, a wire 42 leading from the windings of said solenoid to a common return wire 43 for arrangement at one side of 100 the elevator shaft. A spring 38 has a conducting contact plug 44 which is arranged to be engaged by the conducting strip 21 of the cam 20 when the car reaches the required position in the landing, so that said plug is 105 placed by the cam to close the circuit between 38-40. The circuit closer 37 is identical in construction with the circuit closer 36, its contact plug being indicated at 45 and its electrodes at 46-47, the latter being 110

connected by a wire 48 to the windings of the solenoid 18. A wire 49 leads from the windings of the solenoid 18 to the windings of the solenoid 19, and a wire 50 leads from the windings of the solenoid 9 to the wire 42 which is connected to the return wire 43.

The operation of my invention is as follows: When the operator wishes to stop the car at any floor he will turn the controller lever 23 to a vertical position, thereby causing the cam 24 of said lever to depress the element 25 and close the electrode 27 against the electrode of the contact 29. When the car reaches the required position with its floor substantially level with that of the floor of the building at which it is to stop the brass contact plugs of the contact box 35 will be depressed by the strips on the cam 20 to close the contacts in the contact box 20 and hence current will pass from the conductor 30 through switch element 25, points 27—29, conductor 34, cam strip 22, circuit closer 37, conductor 48, solenoid 18 conductor 49, solenoid 9, conductor 50 and return conductor 43, thus causing the solenoids 18—9 to be energized with the result that solenoid 9 releases the latch 7 and the solenoid 18 by drawing in its core causes the latter through the stud 17 to move the lever bar 14 in the required direction to open the door. When the car is started in either direction by moving the lever 23 in one direction or the other the cam 24 releases the element 25 and the latter springs upwardly so as to open circuit between 27—29 and close a circuit between 27—28 thus cutting out the solenoids 9—18 and cutting in the solenoid 19, the core of the latter hence causing the lever bar 14 to swing in the direction required to close the door.

From the foregoing it will be understood that the doors to the elevator shaft at the various landings are automatically closed as the car leaves a landing and automatically

opened as it reaches a landing thus insuring safety.

Having thus described my invention, I claim:

1. In apparatus of the class described, electrically actuated door operating means, circuit closers for said operating means, car carried means to actuate said circuit closers, a car carried controlling lever, a cam on said lever and switch devices actuated by said cam and included in the circuits with said door operating means and said circuit closers.

2. In apparatus of the class described a door operating lever bar, solenoids arranged with a common core, the latter being connected to said lever bar, circuits including the windings of the solenoids and also including circuit closers and each of said circuit closers having a push button, and a car carried cam to actuate said push buttons and cause the same to close said circuit closers and a car carried lever and switch devices actuated by said lever and included in the circuits with the said door operating means and said circuit closers.

3. In apparatus of the class described electrically actuated door opening and closing means, electrically operated latch operating means for the door, an electric circuit including the latch operated means and the door opening means, an electric circuit including the door closing means, circuit closers for said electric circuits, car carried means to close said circuit closers, switch devices for said circuits and means to actuate said switch devices.

In testimony whereof I affix my signature in presence of two witnesses.

CLYDE D. LAWRENCE.
